BOW TIE AND INSERT

Filed July 24, 1929

Inventor:
Sigmund Deiches
By George E. Mueller
Atty.

UNITED STATES PATENT OFFICE

SIGMUND DEICHES, OF CHICAGO, ILLINOIS

BOW TIE AND INSERT

Application filed July 24, 1929. Serial No. 330,483.

My invention relates to ready made bow ties and inserts for use in such ties.

It is customary to employ some type of insert in a bow tie at the present time. While in general the use of these inserts results in the production of a better ready made bow tie some of them leave very much to be desired in several respects.

In the development of my invention my principal object was the production of an improved insert.

Another object is to produce a ready made bow tie which will have a more natural appearance.

Other objects and features of the invention will be apparent from a consideration of the detailed description taken with the accompanying drawings wherein

Fig. 1 shows a ready made bow tie made in accordance with my invention;

Fig. 2 is the wire insert for use therewith;

Fig. 3 shows the manner in which the wire insert is laid out upon a piece of fabric preparatory to producing the finished insert;

Fig. 4 shows the finished insert;

Fig. 5 shows the manner in which the insert is inserted into the tie proper, and

Fig. 6 is a modified form of the insert frame.

As the drawing shows the usual ready made bow tie is formed with a pair of bags 10 and 11 secured in the center by a knot piece 12 and fastened by suitable means to a neck band 13. The bags 10 and 11 are formed into wings or bows by the knot piece 12 being tight around the center thereof. In the usual tie made according to my invention the front bag 10 is provided with a moldable insert while the rear bag 11 is simply provided with the usual lining although of course this can also be provided with a moldable insert if desired.

The insert proper is shown in Fig. 2 in the form of a rectangular frame 14 having a bracing cross piece 16 connected to the ends of the rectangular frame and disposed midway between the sides 14a and 14b and parallel therewith. This frame is constructed of moldable or pliable material preferably metal and in the simplest and preferred form of

my invention this frame is formed of pliable wire such as German silver.

This frame can of course be used in many ways inside the tie bows but I have obtained the best results by stitching it into the lining of the bow as shown in Figs. 3 and 4. The lining is cut in a long narrow strip 17 a little more than twice as long as the frame. In assembling the frame with the lining the lining is folded over the frame so as to be doubled and stitching 18 is provided all around the frame to hold it firmly in place. The result is a rectangular composite insert as Fig. 4 shows. The bag portion of the tie 10 (Fig. 5) which is made of silk is produced preferably by having a middle opening 10a. The silk is shown folded back along a portion of this opening to illustrate the manner in which the insert is placed within the bag or bow portion. In the type shown one end of the bag 10b is shaped in the form of a triangle the edges 10c being turned in and stitched to close the bag along this entire end.

The insert of my invention is of particular advantage with a tie of the type shown wherein the triangular end piece 10b is provided. When the upper and lower supports are bent inwardly or toward each other to shape the bow tie, the center or longitudinal brace 16 remains straight. This results in a triangular form of the end members 14c and 14d, whereby the insert is given a form similar to the triangular end of the tie. Although the insert does not extend into the end of the tie, the triangular form aids materially in shaping the bow, and this together with the longitudinal brace, gives added body to the tie.

Fig. 6 shows a modification of the wire frame made from thin sheet metal and stamped out in a single piece. This offers many advantages and is the type I prefer to use for certain purposes.

In order to acquaint those skilled in the art with the details of my invention I have described the same with considerable particularity. I wish it understood, however, that the scope of the invention is defined by the appended claims.

What I claim as new and desire to protect by United States Letters Patent is:

1. An insert for a bow tie including a rectangular frame formed of pliable metal and a member of pliable metal connected to the frame and extending longitudinally across the same.
2. An insert for a bow tie including a metal wire frame formed of a single piece of wire, and having a rectangular peripheral portion and a longitudinal bracing piece interconnecting mid-portions of short sides of the rectangular peripheral portion.
3. In a bow tie, the combination of a hollow silk bow section of general rectangular shape, but having an integral triangular portion at one edge thereof, and an insert in the bow including a rectangular metal frame and longitudinal brace therefor, said insert filling the bow section, and said brace holding the insert in shape along the edge of said triangular portion.
4. An insert for a bow tie including a rectangular metal wire frame formed of a single piece of wire and consisting of two longitudinal portions and two end portions interconnecting the longitudinal portions, one of said end portions being spliced at its mid-point, and a longitudinal brace extending from said splice to the mid portion of the other end portion.

In witness whereof, I hereunto subscribe my name this 20th day of June, 1929.

SIGMUND DEICHES.
